REGISTER

Loring Pickering Crosman, Maplewood, N. J., assignor to Gardner Company, Orange, N. J., a corporation of Delaware

Application March 9, 1935, Serial No. 10,271

2 Claims. (Cl. 235—60)

The invention has relation to means for transferring a total accumulated in one accumulator into another or grand total accumulator, and it consists in the novel construction and combination of parts as set forth in the appended claims.

The invention is shown as applied to a listing calculator of the well known Gardner construction, illustrated in U. S. Patent 1,867,002, issued July 12, 1932 to Clyde Gardner, deceased; as modified by the disclosure of U. S. Patent 1,915,296, issued June 27, 1933 to Loring P. Crosman, and by the disclosure of co-pending application Serial No. 10,270 filed by Loring P. Crosman of even date herewith.

15 In the accompanying drawings illustrating the invention:

Fig. 1 is a plan view of a machine embodying the invention.

Fig. 2 is a vertical section through the keyboard, accumulator and printing mechanism.

Fig. 3 is a right side elevation of the accumulator control mechanism and associated parts.

Fig. 4 is a similar view of the accumulator control mechanism in position assumed upon setting 25 of the total transfer lever.

Fig. 5 is a similar view, showing the parts in position assumed with the transfer total lever set and the total key depressed.

Fig. 6 is a similar view with the parts in position assumed during a transfer total operation.

Fig. 7 is a left side elevation of the machine with the casing removed and parts broken away.

Fig. 8 is a right side elevation of the machine with the casing broken away.

35 Fig. 9 is a detail right side elevation of parts omitted from Fig. 3.

In the machine illustrated, amounts set up on the digit keyboard 215 (Figs. 1 and 2) are accumulated in one or in both accumulators 473, either 40 additively by engagement of an accumulator during the upward stroke or subtractively by engagement thereof during the downward stroke of reciprocating actuating segments 610. The segments are reciprocated by movement of a rock shaft

45 301, preferably driven by electric motor 100, said rock shaft having a cam 318, adapted to move a rocking frame 616, and thereby cooperating with the springs of the segments to effect movement thereof. The extent of movement of each segment is limited by engagement of a stop bar 615 carried by the segment, with the lower end of a depressed key 215, whereby this extent of movement will correspond to the value of such depressed key. Type bars 611 are connected with the segments 610, and are raised thereby to

bring the appropriate type to the printing line. Before the return of the adjusted segments by the frame 616, spring type hammers 715 will be released by triggers 701, to print the item on a record sheet.

5

Plus and non-add setting

The accumulators 473 are set to give the desired registration by means of two cam plates 419, 421 (Fig. 3) pivoted in the frame at 420 and 422, 10 respectively, these plates cooperating with cams carried on the shafts 403 of the accumulators. From the position illustrated in Fig. 3, the cam plates 419, 421 are rocked toward each other by means of a rocker device 325, (Figs. 4 and 6) connected with the cam plates by members 322, 321, and operated by cam arms 320, 316, fixed upon the rock shaft 301. Rocker device 325, as set for normal operation, provides for movement of plates 419, 421 toward each other, as soon as the machine is put in operation, and before the movement of segments 610. At the beginning of the return movement of shaft 301, rocker 325 will be operated in a reverse direction, to return the cam plates 419, 421 to the position illustrated in Fig. 3 before 20 the return movement of segments 610 is begun. Each of the cam plates 419, 421 is provided with two cam faces, 452, 454, these cam faces being offset from each other transversely, and lying in different circumferential angular positions. In 25 the position illustrated in Fig. 3, the cam faces 452 of the plates are opposite the shafts 403, whereas, upon movement of the plates by rocker 325, the cam faces 454 thereof will be brought opposite the shafts 403.

35 Each shaft 403 is provided with a cam 453, lying in the plane of the related cam face 452, and a cam 455, lying in the plane of the related cam face 454. The shafts 403 may be held in either of three rotated positions, whereby the high points of cams 453 or 455, or the low points of both cams may be brought opposite the cam faces of the plates 419, 421.

The shafts 403 are urged by spring means (not shown) away from the segments 610, suitable 45 guides in the frame of the machine being engaged by said shafts. Thus, the shafts 403 will hold the accumulators 473 out of mesh with the segments 610 unless a cam face 452 or 454 is engaged by a cam 453 or 455, in which case the 50 accumulator will be thrown into mesh with the segments.

It will be seen that the low point position of the cams 452, 454 provide a non-add adjustment for the accumulator 473. To set the accumulators 55

for addition, the cams 453 are rotated to active position in which the accumulators will stand in engagement with the segments 610 when the machine is at rest; will be allowed to drop out of mesh with the segments as soon as the machine is put in operation and will be reengaged with the segments at the beginning of the return stroke thereof. It may be noted that the upper accumulator is set for addition in Fig. 3, the lower accumulator being set for non-add.

These settings of the accumulators are controlled by a lever 1 (Figs. 1 and 7), which, as shown, is set to a position indicated by the letter "A" on a display plate shown in Fig. 1. This designation shows that this "A" or upper accumulator is set for addition and that the lower or "B" accumulator is left inactive, or in non-add position, during operation of the machine by the normal operation key 114.

20 Total printing

A total is taken by releasing the differential stop bars 615 and allowing them to rotate the accumulators subtractively until suitable pins 25 on the accumulator wheels contact with 0 stop members. This will set the total in the type bars, and the hammers will be tripped to print the total. The bars 615 are then reengaged with the oscillating frame and during the return 30 stroke of said frame are moved rearwardly to normal position, the accumulator wheels being disengaged from the racks before the return stroke is made, whereby the accumulator which has been totalized will stand at 0.

35 The machine is set for reverse or subtractive operation by contact of the total key lever with a pin 352 (Fig. 4) on rocker control plate 326, the total key thus holding the plate out of the path of clockwise rotation of the forward cam 40 follower, so that the accumulators will not be disengaged at the beginning of the operation, by the action of cam arm 320. On the return stroke of the parts, the forward cam follower, coacting with cam arm 320, will disengage the active 45 accumulator from the segments. The described setting of plate 326 also disables the rear cam follower. At the end of the cycle of operation a pin 350 (Fig. 3) will contact with arm 322 and restore rocker 325.

50 Depression of the total key 278 will not only trip the column latches 214 (Fig. 2), through pin 263 and rocker 221 (Fig. 3), but will also trip a latch 620, through operation of a control arm 621 pivotally connected to said latch. Latch 55 620 normally engages a lug on total segment 618, preventing movement of said segment under the influence of the total spring 681. Upon tripping of the latch, segment 618 will operate a shaft having a spirally arranged row of pins 651 (Fig. 62), acting to trip the latching dogs 617 successively from right to left of the machine, the tripping of said dogs releasing the segments and also releasing stop members 613, so that they will fall into the path of the 0 stops 457 on the accumulator wheels.

When this zeroizing operation has progressed to the left hand side of the machine, a rearwardly extending arm of the total segment 618 will contact with a projection of a rod 130 (Fig. 3) connected at its other end to a trigger 131, adapted to release latch 112, and thereby engage a clutch connecting rock shaft 301 with motor 100. The machine being put in operation, frame 616 will carry the dogs 617 forwardly, so that they will

5 snap under the stop members 613 and studs 659 of the segment levers. The hammers will now be tripped, and upon rearward movement of frame 616 the segments and total stops will be restored to normal position.

The total key is locked in depressed position by latch 223, and is released near the end of the cycle of motor operation by engagement of a finger of rock arm 327 (Fig. 3), driven by parts 324 and 316 (Fig. 6) above a click pawl 222 of 10 latch striker 220, the parts of the total setting mechanism being then restored to normal position.

The mechanisms above set forth are all described in detail in the patents and application 15 hereinbefore referred to.

Transfer totals

Provision is made whereby the setting of a transfer total lever 61 (Figs. 1 and 7) will set 20 mechanism into position to be operated by the total key 278 whereby the lower or "B" accumulator will be thrown into add position during the total printing operation, so that the total cleared from accumulator "A" and printed on 25 the record sheet will be accumulated as a grand total in "B" accumulator.

Lever 61 is fulcrumed on a shaft 62 and at its lower end contacts with a pin carried on a crank arm 63 of said shaft, setting of the lever by 30 counter-clockwise movement from the position shown in Fig. 7 serving to rock the shaft 62, against the tension of a spring 64. Shaft 62 is held in rocked position by engagement of a pin of lever 61 with a cam slot 69 of an interlock plate 65, pivoted at 66 in the framing, and provided with a notched portion adapted to register with a pin 67 fixed in the control lever 1. If control lever 1 is not located in "A" position, pin 67 will not be opposite the notch of plate 65, and said 40 plate will prevent the setting of transfer total lever 61. The cam walls 68 of the notch of plate 65 also serve as a means for releasing lever 61 from the locking action of cam slot 69. Thus, when it is desired to reset the control lever, the 45 transfer total lever is automatically restored to inactive position.

In addition to the crank arm 63, shaft 62 is provided with two arms 70 and 71 (Fig. 3) on the right hand side of the machine. Rocking of 50 shaft 62 by lever 61 will move the arm 70 from the position shown in Fig. 3 into that illustrated in Fig. 4, in which position, a dog 72, carried by said arm will be positioned beneath a pin 73 in the total key lever.

With lever 61 set in active position, the depression of total key 278 will, through engagement of pin 73 with dog 72, rock arm 70, shaft 62 and arm 71 into the position illustrated in Fig. 5. This movement will serve, through a link 74 to raise a hook 75, pivoted to a cam plate 76, into latching engagement with a pin 77 of the cam plate 419, so that the plates 76 and 419 are rigidly connected for operation in unison. Dog 72, which is connected with the arm 70 by a pivot and also by a spring 78, serves to hold the hook 75 in engagement with pin 77 during the subsequent movement of the parts (which may rock arm 70 slightly, Figs. 5, 6), due to the action of 70 the spring 78 in holding said dog against pin 73.

It has been explained that during a total printing cycle of operation, cam plate 419 will remain in the position illustrated in Fig. 5 during the forward stroke of the actuator frame 616, 75

and that before the return movement of this frame, with the segments 610, plate 419 will be rocked upwardly, into the position shown in Fig. 6. When hook 75 is engaged with pin 77, this upward movement of plate 419 will raise the cam plate 76 therewith, bringing a cam portion 79 thereof into engagement with a collar 80, fixed upon the shaft 403 of the lower accumulator, and forcing said accumulator into meshing engagement with the segments. The return of the segments to normal position will, therefore, add the amount taken from the upper accumulator, and set in the type bars 611, into the lower accumulator. The return movement of cam plate 419, 15 near the end of the cycle of operation, and the release and restoration of total key 278, will allow plate 76 to return to the position illustrated in Fig. 4, under the influence of the springs 64 and 78.

20

Negative totals

As set forth in detail in Patent 1,915,296, hereinbefore referred to, amounts accumulated in the higher order accumulator wheels, located to the left of the keyboard are transferred to the printing devices when a total is taken. If the total is negative, the complementary registration in the accumulator will include a 9 in the above-mentioned left hand wheel, and movement of the related type bar from 8 to 9 printing position is utilized to set the true negative total devices in operative position.

The method of converting the complement of a negative total, set in the type bars, to the true negative total is as follows:

A set of stops 143 (Fig. 2), yieldably engaging the stop bars 615 are locked in position as adjusted thereby in accordance with the complementary registration and the segments 610 are restored idly to normal position. The segments are now again released and will be stopped by the stops 143, the accumulator being meshed during this subtractive stroke of the segments, whereby the complement is subtracted from zero, giving a registration of the true negative total. The segments are again restored idly to normal position by a cycle of operation of frame 616, and the stops 143 are released, so that a second zeroizing operation will now transfer the true total to the type bars. The printing of the total, which normally occurs at the end of the first total setting operation has in this case been delayed, and will occur after the true total is set.

In moving from 8 to 9 printing position, the extreme left hand type bar releases setting shaft 146 (Figs. 3 and 8) which will thereupon be rocked counter-clockwise by a suitable spring. Rocking of shaft 146 suspends the operation of the printing and normalizing devices in known manner.

The release of the total key from its latch 223 (Fig. 3) is prevented by an arm 150 connected by link 151 with arm 152 of setting shaft 146, arm 150 being held in the rocked position of the shaft 65 in engagement with pawl 222 mounted on the latch striker 220, so that said pawl may not be operated to actuate the striker so long as setting shaft 146 remains in rocked position. Total key 278 thus remaining latched in operative position, 70 the subsequent operations will all be of a subtractive nature, and the column latches 214 will remain inactive.

The first operation of the totaling mechanism 5 under the influence of spring 681 has served to

engage the motor clutch, for the purpose of restoring the segments, etc., and in order that a second cycle of the motor drive mechanism may be secured, in which the subtractive operation of the accumulator will occur, the clutch will be held in operative position as follows:

A latch arm 157 (Fig. 8) will be carried downward by shaft 146 out of engagement with a latching pawl 158 mounted on a plate 159, pawl 158 being held upward, to permit the disengagement, by a second latching pawl 170. Plate 159 being released from the latch, will be drawn rearwardly by spring pressed member 160 (Fig. 3) and a lug of plate 159 will engage the hook end of link 130 (now in its lower position) connected to the trigger 131, holding this trigger out of latching engagement with the clutch lever 106.

In order to lock the segment stop members 143 in the positions assumed during the preliminary total taking, the plate 159 is provided with a pivoted extension 163 (Figs. 3 and 8) which, in the rearward movement of plate 159 is held under tension against the pin 164 mounted on one end of an intermediately fulcrumed lever 165.

The consequent relative movement of plate 159 and extension 163 will release latching pawl 158 from the restraint of the second latching pawl 170, the former pawl falling upon latch arm 157. The forward arm of lever 165 operates a locking bail 166, engaging serrations of the stops 143, the lever being normally operated by a double faced cam 167 secured to arm 316 of operating shaft 301. As arm 316 moves forward rocking bail 166 is released, by the action of cam 167, while in the rearward movement of arm 316 the cooperating roller of lever 165 will ride the upper face of cam 167, whereby the locking bail is brought into contact with the stops 143. This will be the operation of the parts during the first cycle of motor operation, which restores the segments. As the rear end of lever 165 is lifted by cam 167, however, in the return movement of the parts, pin 164 will be lifted free of extension 163, and said extension will immediately move under the pin, holding locking bail 166 in engaging position, where it will remain during the subtractive stroke of the second cycle of motor operation, that is to say, while the segments move the wheels subtractively from 0 registering position to the extent allowed by the stops 143. At the end of this stroke a pin 168 in arm 316 will engage a seat 169 in extension 163 and will move plate 159 and its extension 163 forwardly, in which position the parts will be held by latching pawl 158, moving into engagement with the shoulder of latch arm 157.

The true negative total being now registered in the accumulator, a second totalizing operation, occurring on the final motor operation cycle and accomplished by the means hereinbefore described, will result in the printing of the true negative total. The total latch is controlled to initiate this second totalizing operation as follows:

It has been seen that, because of the negative condition of the accumulator, the total key is held in depressed position, which, ordinarily, would result in the tripping of the total latch 620 at the end of the cycle of motor operation (first cycle) which serves to restore the segment levers 610. This tripping action would occur because pin 132 in the latch-operating arm 621 (Fig. 3), held depressed by key 278 and arm 229, is contacted by shoulder 133, as rocker cam 318 re-

65

70

75

80

85

90

95

stores push rod 135 to normal position, tripping latch 620.

This tripping action is delayed until the completion of the subtractive operation of the machine by the adjustment of a member 173 (Fig. 9) pivoted upon an arm 172 of shaft 171, said member lying normally between rocker cam 318 and push rod 135. Shaft 171 is rigid with plate 159, and, as said plate moves rearwardly at the end 10 of the first total setting operation, pivoted member 173 will be carried out of register with rocker cam 318, so that, upon the subsequent return of said cam to normal position, push rod 135 will not be operated. During the subtractive cycle of operation, however, plate 159, being restored to normal position by pin 168 and part 169, pivoted member 173 will be restored to position beneath rocker cam 318, and at the end of this cycle the push rod will rock plate 134 and trip the total 20 latch.

This tripping movement of push rod 135 is utilized to restore setting shaft 146 to normal position. For this purpose shaft 146 is provided with an arm 175 carrying the pawl 176 which, as 25 shaft 146 is rocked forwardly is held by spring 177 in contact with a shoulder 178 of push rod 135. As the rod is moved downwardly, pawl 176 and arm 175 will rock the setting shaft back to normal position. Setting shaft 146 and the parts 30 controlled thereby being restored to normal position, and total latch 620 being tripped, an ordinary total taking operation will now occur.

Since the taking of a negative total will involve three reverse operations of the rocker 325, the 35 plate 419 will be moved at each cycle of operation from the position shown in Fig. 5 to that illustrated in Fig. 6, and if the transfer total lever 61 is set to active position at this time, three additive movements of the lower accumulator will be effected. Near the end of each of these cycles of 40 operation the plate 419, in moving to its lower position will contact with the stud of hook 75 and move plate 76 also into its lower position. During the first cycle of operation, the complementary 45 registration taken from the upper or "A" accumulator will be added into the lower or "B" accumulator, and during the second cycle this same amount, which has been locked in the stop members 143 will be added into "B" accumulator a 50 second time. During the third cycle, the true negative total taken from "A" accumulator will be added into "B" accumulator, the result being that, the two last named operations being complementary to each other, and thus cancelling out, the 55 complementary registration which originally stood in "A" accumulator will be correctly transferred

to the "B" accumulator. This may be better understood from the following example:

"A" accumulator "B" accumulator

999,999,940.	000,000,000.
-999,999,940.	+999,999,940.
-999,999,940.	+999,999,940.
-60.	+60.

000,000,000.	999,999,940.

5

10

It will be seen that the correct result in "B" accumulator is secured by the provision of means for registering the complement of the original total additively in one accumulator and subtractively in the other. It is obvious that such 15 means would operate to transfer the complementally registered total correctly by the more direct method illustrated in the following example:

"A" accumulator "B" accumulator

999,999,940.	000,000,000.
+60.	-60.

000,000,000.	999,999,940.

20

25

It should be noted that the "complement of the original total" above referred to is the complement of a complementally registered total, and comprises the true negative total.

I claim:

1. In a register, the combination with two accumulators, means including selectively settable elements for adjusting said accumulators for add, subtract or non-add operation, and total printing means including a key operable to clear a total 35 from either appropriately adjusted accumulator and to effect the printing; of normally inactive means adapted to cooperate with said adjusting means to adjust a given accumulator to register a total cleared from the other accumulator, and means settable to hold said normally inactive means in position for operation by the total key.

2. In a register, the combination with two accumulators, means including selectively settable elements for adjusting said accumulators for add, subtract or non-add operation, and total printing 45 means including a key operable to clear a total from either appropriately adjusted accumulator and to effect the printing; of means including a normally inactive cam adapted to adjust a given 50 accumulator to register a total cleared from the other accumulator, a latch adapted to connect said cam with the first-named adjusting means, a latch engaging device, and means settable to hold said engaging device in position for operation by 55 the total key.

LORING PICKERING CROSMAN.
